(57) **CLAIM**

The ornamental design for a bonded panel having interlocking sides, as shown and described.

DESCRIPTION

FIG. 1 is a perspective view of a bonded panel having interlocking sides showing our new design, the broken lines showing a second bonded panel are for illustrative purposes only and form no part of the claimed design; and the broken lines shown in the openings between the two panels is to illustrate the alignment of the two panels.

FIG. 2 is a front elevational view of a bonded panel having interlocking sides of FIG. 1, the rear being a mirror image thereof;

FIG. 3 is a right side elevational view of FIG. 2;

FIG. 4 is a left side elevational view of FIG. 2; and,

FIG. 5 is a top plan view of FIG. 2, the bottom plan view being a mirror image thereof.

The bonded panel having interlocking sides is shown as broken in FIGS. 1-4 to indicate indeterminate length.
